United States Patent Office

Des. 177,438
Patented Apr. 10, 1956

177,438

BOW TIE

Emery C. Smith, Bridgeport, Conn.

Application March 25, 1955, Serial No. 35,216

Term of patent 7 years

(Cl. D3—16)

Fig. 1.

Fig. 2.

Fig. 1 is a front view of a bow tie showing my new design, and

Fig. 2 is a top view thereof.

The predominant features of the design are in the portion shown in full lines.

I claim:

The ornamental design for a bow tie, substantially as shown and described.
